DESIGN FOR A TEXTILE FABRIC

Walter Hoegger, New York, N. Y.

Application March 8, 1939, Serial No. 83,414

Term of patent 3½ years

To all whom it may concern:

Be it known that I, Walter Hoegger, a citizen of Switzerland, residing in the Borough of Manhattan, city and State of New York, have invented a new, original, and ornamental Design for a Textile Fabric, of which the following is a specification, reference being had to the accompanying drawing, forming part thereof.

The figure is a plan view of a textile fabric, showing my new design.

I claim:

The ornamental design for a textile fabric, as shown.

WALTER HOEGGER.
